UNITED STATES PATENT OFFICE.

FRED F. CONWILL, OF BERKELEY, CALIFORNIA.

PAD FOR DECORATING.

Application filed January 31, 1927. Serial No. 164,972.

This invention relates to decorating devices and more particularly it pertains to pads for producing a design on walls or other object.

5 One of the objects of my invention is the provision of a pad by which a decorator may simultaneously obtain a stippling effect and produce a design on a freshly painted surface.

10 With the foregoing object in view, together with such other objects and advantages as may subsequently appear, this invention resides in the construction and arrangement of parts hereinafter described and claimed, and illustrated in the accompanying drawings, in which

Figure 1 is a plan view of one form of pad of my invention;

Figure 2 is a section taken on line 2—2 of 20 Figure 1;

Figure 3 is a plan view of an alternative form of pad; and

Figure 4 is a section taken on line 4—4 of 25 Figure 3.

Referring to the drawings for a more detailed description thereof, and at first to Figures 1 and 2, the device comprises a holder 7 having a back 8 and spaced therefrom intermediate its ends an arcuate front portion 9 to which is held a pad 10 of superimposed arcuately-shaped, tissue-thin sheets 11. The adjoining sheets are lightly held together by an adhesive, preferably at spaced intervals around their edge portions so that when the pad is pressed against a surface having wet paint thereon, a sheet will be held by the paint as the pad is removed.

The sheets 11 are herein shown as having a design which consists of a pair of diamond-shaped apertures 12 cut in each sheet, but it is to be understood that embossed designs may also be employed.

After a sheet has been removed from the pad by sticking to the wall, it is manually removed from the wall. While on the wall the sheet, being absorbent, absorbs some of the paint with which it has been in contact and on being removed takes part of the paint with it, leaving a design on the painted surface. Thus the application and removal of the sheets simultaneously produces a stippling effect and a design on the wall.

Coloring matter may be placed on the sheets so that it may be transferred to a painted surface. This coloring matter may also be placed on in the form of a design.

Or the sheet may be impregnated with the coloring matter.

Figures 3 and 4 show a pad similar to the one shown in Figures 1 and 2, except that the back and the pad 16 proper are flat and the design consists of 4 diamond-shaped apertures 17.

While I have described one embodiment of my invention, modifications thereof may be readily devised without departing from the spirit of my invention, and it is to be understood that such modifications come within the scope of the appended claims.

I claim:

1. A pad for the purpose described comprising a holder and a pad proper held thereto, said pad comprising a plurality of superimposed sheets removably held together, said sheets having a design therein whereby, when applied to a coating of wet paint, at least part of the paint will be removed and a design produced in the coating of paint.

2. A pad for the purpose described comprising a holder and a pad proper held thereto, said pad comprising a plurality of superimposed sheets removably held together, said sheets having a design therein whereby, when applied to a coating of wet paint, at least part of the paint will be removed and a design produced in the coating of paint, said sheets being absorbent.

3. A pad for the purpose described comprising a holder and a pad proper held thereto, said pad comprising a plurality of superimposed sheets removably held together, said sheets having a design therein whereby, when applied to a coating of wet paint, at least part of the paint will be removed and a design produced in the coating of paint, said sheets being very thin.

4. A pad for the purpose described comprising a holder and a pad proper held thereto, said pad comprising a plurality of superimposed sheets removably held together, said sheets having a design therein whereby, when applied to a coating of wet paint, at least part of the paint will be removed and a design produced in the coating of paint, said sheets being absorbent and very thin.

5. A pad for the purpose described comprising a holder and a pad proper held thereto, said pad comprising a plurality of superimposed sheets removably held together, said sheets having a design therein

whereby, when applied to a coating of wet paint, at least part of the paint will be removed and a design produced in the coating of paint, said sheets holding coloring matter adapted to be transferred to the coating of wet paint.

6. A device of the type described, com-

prising a holder having a convex surface, and a sheet of absorbent material disposed on the convex surface, said sheet having characters cut therein and being removable from said holder when applied to a freshly painted surface.

FRED F. CONWILL.
